FIGURE 1 is a perspective view of a building showing our new design;

FIGURE 2 is a top view;

FIGURE 3 is an elevational view of the side not shown in FIGURE 1; and

FIGURE 4 is an end view.

The other end appears substantially similar to the end shown. Each of the end portions simulates a major segment of a doughnut, with the hole of the doughnut operating as the drive-in entrance.

The dominant feature of our design resides in the portions shown in solid outline.

We claim:
The ornamental design for a building, substantially as shown and described.
